CONTAINER PACKAGING APPARATUS

Richard A. Smith, Pittsburgh, Pa., assignor to
 H. J. Heinz Company, Pittsburgh, Pa., a corpora-
 tion of Pennsylvania

Application August 10, 1951, Serial No. 241,221

26 Claims. (Cl. 226—14)

1
 This invention is for an apparatus for inserting containers into packages or cartons having partitions or cells therein so as to place one container in each cell.

The invention has special application to the packaging of filled bottles, as for example, bottles of ketchup or vinegar, into cardboard shipping cartons. These cartons are constructed with crossing partitions, dividing the interior into cells, each one of which is designed to snugly receive and hold a single bottle. The invention will be particularly described in connection with such use, but it is also applicable to putting other sealed containers, or like articles, into such shipping receptacles so divided.

In the operations for which this invention is especially applicable, bottles are filled and sealed, and then delivered to a labeling machine where paper labels are applied to the containers. While the labels are still moist, the containers are carried to the packing station to be put into the cartons. Of course, this operation proceeds at a relatively high speed. Formerly, the bottles were placed in the cartons individually by hand labor. Even with hand packing, the labels might be rubbed against the cell walls or partitions and damaged. Machines have been developed for collecting the required number of bottles into groups, and then the bottles dropped into a carton, falling a sufficient distance to assure that they had enough momentum to drop to overcome the friction of the cell walls and cause the bottle to fully enter the case. Such machines cause frequent breakage that not only means a loss of the contents of the containers, but also damages the carton and requires the rehandling of the other bottles in the carton. Damage to the labels is also incident to this type of machine.

Other machines have been devised wherein the bottles are grouped on a conveyor and an operator then places an inverted carton over the group of bottles and presses it down. The bottles enter the cells top end, or neck end first, which is of assistance in slipping the inverted carton over the bottle, but the bottles are initially in contact with one another and the partitions in the carton must be relied upon to spread them apart as the carton is pushed down. This is likely to result in extensive damage to the labels, unless bottles are used having annular beads above and below the label.

The present invention pertains to apparatus of that type in which the carton is inverted and slipped over the tops of the bottles. It has for its object and provides, however, for the sepa- 55

2
 ration of the bottles in such manner as to avoid damage to the labels. It further provides a unique arrangement for inverting the cartons after they have been slipped over the bottles, and for jarring the bottles into the cartons after the inverted carton has been partially applied over the bottles.

Among other objects of the invention are the provision of means for arranging the bottles into groups of the requisite number and isolating a group from succeeding bottles, and the provision of a machine which is readily adapted for taking care of different sized bottles. For example, the machine may be adjusted for use with quart vinegar bottles, pint vinegar bottles, ketchup bottles, etc., depending upon the pack that is required to be run.

Another feature of the invention is the automatic positioning of bottles so that cartons having individual cells for each bottle may be easily and quickly moved over the bottles, with each bottle in its proper cell, to permit the packaging of a large number of bottles per minute.

5
 Ketchup bottles, which have a long tapering neck are adapted for placing the carton having cells therein over them while in the assembly rows. But with large bottles which have a short narrow neck, it has been found of great assistance to an operator, to separate an assembled carton group of bottles from the assembly line to allow the carton to be placed over the group.

Accordingly, another object of the invention is to provide a mechanism to move a carton filling group of bottles on a table a short distance away from the assembly line to facilitate positioning a carton over the group and then after a carton has been placed on the bottles discharging the loaded carton from the table.

My invention may be more fully understood by reference to the accompanying drawings, where-
 in:

Fig. 14 is a view in side elevation of the table stop cam; and

Fig. 15 is a detail plan view of the tilting table.

The container packaging machine illustrated in the drawings is arranged to receive containers which have been filled and sealed or capped while in a scrambled condition. The scrambled containers are then advanced into the path of distributing plates for distributing the containers in lanes or rows to arrange them to be placed in a carton containing cells. A tilting table is arranged at the end of the distributing conveyor and containers are positioned on the table in an arranged order for guiding the containers into the cells of the carton. If the containers are bottles, the carton with an open top is placed over the top of the bottles, and when the carton has been pushed in position, a switch is arranged to move the tilting table to turn the carton upside down and land it upon a conveyor belt which will conduct it to a gluing machine for gluing the bottom flaps of the carton. The packaging operation is carried on continuously and a single operator may place the cartons over the arranged bottles in order to package ketchup, for example, at the rate of six hundred bottles per minute.

The packaging machine is supported upon a table 16 which consists of channel irons 18 extending longitudinally of the table and resting on a post 20 at each end, Figs. 1 and 3. Longitudinal braces 22 and transverse braces 24 extend between the posts near the base thereof.

The main conveyor belt 26 is mounted to run over substantially the entire length of the top of the table. The belt runs over rollers 28 which are supported on shafts 30 journaled between the channel beams 18 at each end thereof. The belt is preferably a woven wire belt having a herringbone weave such that the belt will run continuously, and, if the containers are stopped from movement with the belt, the action of the belt on the base of the containers will tend to urge the containers forward in a direct line without causing transverse movement of the containers. This construction is important in maintaining the containers in direct lines for moving them onto the tilting loading table. Belt tighteners 32 are mounted at each side of the table for the purpose of adjusting the shaft 30 to keep the belt tight and properly positioned upon the rolls 28.

The conveyor belt is driven by a motor 34 which is supported on channels 36 secured to the longitudinal braces 22, Fig. 1. A pulley 38 is secured to the motor shaft and a belt 40 runs between the pulley 38 and a pulley 42 secured to the shaft of a speed-reducing mechanism 43, Fig.

2. The speed-reducer has a shaft 44 upon which is mounted a sprocket 46 and a sprocket chain 48 runs between the sprocket 46 and a sprocket secured to the end of a shaft 30 journaled in the rear end of the table 16. A hand wheel 50 is mounted below the motor 34 by which the speed-reducer 43 may be adjusted for varying the speed of the conveyor belt 26.

The loaded containers are advanced upon the conveyor belt 26 into an assembly section 52. The assembly section is confined between guides 54 which are mounted to be adjusted transversely of the belt in order to position the containers so that they will advance into two, four or six lanes to prepare them for movement upon the tilting table. When the containers reach the section 52 they have no definite arrangement, but the containers leaving the section 52 advance in rows. The rows being arranged by distributing plates 56, as shown in Figs. 2 and 3. Seven plates are positioned above the belt with their front ends projecting into the assembly section 52. The plates 56 are suspended from cross bars 58, 60 and 62, Fig. 2, which are mounted in frames 64 supported on the channels 18 at each side of the table 16. The transverse bar 62 is fixed in position on the frame 64 and the plates 56 have a pivotal mounting in the bar 62. The transverse bars 60 and 58 are movably mounted upon the frames 64 and the plates 56 are pivoted to move with the bars 60 and 58.

An oscillating movement across the belt is imparted to the plates by means of a motor 66, Fig. 2, which is mounted on a frame 64 adjacent the front end of the plates 56. A cam 68 is secured to a shaft 70 extending outwardly from a speed-reducing mechanism 72 connected with the motor 66. The cam 68 receives a yoke 73 attached to the end of the bar 58. The cam 68 is eccentric and imparts a reciprocating movement to the bar.

The belt 26 constantly urges the container in the section 52 forwardly and the oscillating plates 56 tend to move the containers into position to enter a lane between the plates. After the containers enter the lanes, they move forwardly in rows and advance to a stop 74 at the rear end of the table 16, Figs. 1, 4 and 5.

As shown in Fig. 2, the ends of the plates 56 are not in a common plane, but alternate plates extend different distances toward the assembly section 52. This arrangement of plates is necessary when aligning containers which have flat sides. For example, ketchup bottles are octagonal, and other bottles are hexagonal. If the ends of the plates were in a common plane, some of the plates would tend to move against the flat portions of the bottles, and their distribution in the lines would be interferred with. By having the plates extend different distances in the line of travel, the flat surface bottles are properly arranged in the lanes. With circular bottles the ends of the plates 56 may be in a common plane, and still have the bottles properly distributed in the lanes.

As the containers are presented to the packaging machine, they contain labels. Generally, the containers advance from a label machine to the packaging machine so that the labels may have been newly applied and are easily removed. To avoid disturbing the labels on the containers, the plates 56 have a cut-out portion 76 in the front ends thereof which is in the position of the label on the containers. Therefore, the container will engage the front end of the plates 56 either below

or above the position of the label on the container. To further assist the plates in their oscillating movement in distributing the containers in the lanes, beads 78, Figs. 7 and 8, are secured to the bottom of the plates in order to engage rounded bottom containers and assist in moving them into position where they will enter the lanes. The beads furthermore help to protect the labels so that they will not be injured by the ends of the plates 56.

The containers are advanced from the lanes between the plates onto a tilting table and arranged in proper position to receive a packaging carton. The tilting table is shown more particularly, in Figs. 2, 4, 15 and 6. The table consists of a convex plate 80 which is secured to brackets 82 mounted on a tubular member 84. The tubular member 84 is rotatably mounted on a shaft 86 which extends between channels 18 at each side of the table. In accordance with the size of the container and the number of containers to be placed in a carton, a series of plates 88 are mounted on the plate 80 to accurately space the containers to receive the carton. The end plate 88 has a stop 90 which limits the movement of the containers advanced from the conveyor belt. The stop being adjustable by means of washers 92 to provide any desired position of the containers. As shown in Fig. 2, a series of slots 94 are formed in the plate 80 to receive bolts by which the plates 88 may be attached to the plate 80. Furthermore, across the plates 88 are mounted guides 96 which form extensions of the plates 56 for arranging the containers in rows across the table. For different sizes of containers, the plates 56, the guides 96 and plates 88 must be arranged and adjusted.

After a carton has been placed over a group of containers or bottles, the loaded carton is turned upside down and received on a conveyor belt. The table is tilted by means of pneumatic plunger 98 which is pivoted to a bracket 100 secured between the posts 20 at the rear end of the supporting table. The operating mechanism for the pneumatic plunger is illustrated in Fig. 1 and 3. Air for operating the plunger is received through a line 102 and passes through pressure regulating valves 104. The air flows from the valves 104 through a line 106 to a four-way valve 108. The valve 108 is operated by means of solenoids 110 and 112 which are mounted at each side of the valve. Air from the valve 108 flows through a line 114 to make a connection with the lower end of the plunger cylinder 98. A second air line 116 connected with the valve 108 is connected with a fitting 118 to supply air through a line 120 to the upper end of the plunger cylinder 98. The plunger has a piston rod 122 extending upwardly to connect with arms 124 which are secured to the sleeve 84. Therefore, when the piston rod is moved downwardly by introducing air into the upper end of the plunger cylinder, the table will be tilted to the position illustrated in Fig. 5. When the table has been tilted far enough to over-balance the filled carton, the carton will be thrown upside down and land upon a conveyor belt 126 positioned in front of the table 16. The conveyor 126 is mounted on springs 128 so that the conveyor belt will yield under the impact of the filled container striking the belt to prevent the containers from being broken. Furthermore, the conveyor belt 126 is preferably made of fabric impregnated rubber, and the belt is arranged with reference to the packaging machine to provide a long span so that the belt can yield under the

impact of the filled containers without danger of breaking glass bottles for example.

When a carton has been filled with containers, the table is put into tilting operation by a foot-operated electric switch 130 which is mounted at the rear end of the table 16, Fig. 1. The switch is closed by the foot of an operator who is engaged in placing the cartons over the arranged containers on the table. When the switch 130 is depressed, a solenoid 110 will operate the valve to admit air to the upper end of the plunger. The plunger will impart a direct oscillating movement to the table to discharge the filled container from the table. The tilting movement of the table is limited by means of a stop 132, Fig. 1, which is mounted on a channel 18 of the table in the path of movement of the convex plate 80. When the plate 80, Fig. 1, has moved downwardly to engage the stop 132, a switch 134 connected with the stop 132 will be actuated to energize the solenoid 112 for the purpose of supplying air to the lower end of the plunger for moving the table back into loading position. When air is introduced through the line 114 to move the table back into loading position, the air acts on the piston in the plunger continuously until the switch 130 is again operated to tilt the table. The air thus acts to positively hold the table in loading position, as illustrated in Fig. 4.

At the time the table is tilted, the container stop 74 is moved up into the path of the containers moving through the lanes between the plates 56. This upward movement is obtained by means of a pneumatic plunger 136, Figs. 1, 3 and 4. The lower end of the plunger 136 is connected by means of an air line 138 which extends from the fitting 118 to the bottom of the plunger. At the time that air is introduced into the plunger 98 for tilting the table, air is simultaneously introduced into the bottom of the plunger 136 to force the piston rod 140 upwardly to push the stop 74 above the top of the belt 26 on the table. As illustrated in Figs. 1 and 3, a needle valve 142 is connected with the upper end of the plunger 136 by which air may slowly leak from the plunger to prevent excess pressure being placed upon the piston rod. The table plate 80 normally rests upon the top of the stop 74 and acts to move the plunger down against the action of the piston. When the table is lifted during the tilting motion the pressure applied by the piston rod 140 will automatically move the stop 74 into the path of movement of the containers advancing through the lanes. Therefore, the movement of the table upwardly will permit the stop to move into stopping position and the positive movement of the table downwardly into loading position by the plunger 98 will force the stop down, thus permitting the containers to advance onto the table as soon as the table reaches the loading position. When the solenoid 112 is operated to cut-off the air from the line 116, the pressure on the piston rod 140 and stop 74 is removed and air escapes from the plunger cylinder.

A carton is applied to bottles such as ketchup bottles while the table is in loading position as illustrated in Fig. 4. It will be seen that the ketchup bottle has a long tapering neck which allows an operator to readily place an open carton over the bottles to position a bottle in each cell of the carton. All containers are not the same and as illustrated in Fig. 9, a large vinegar bottle has a short neck and comparatively large body. It has been found that it is rather diffi-

cult to position an empty carton over vinegar bottles when the bottles are on the table in loading position.

Accordingly, when packaging vinegar bottles the table tilting operation is carried out in two steps. After the table has been filled with containers, the switch 130 is operated to tilt the table and when the table has been tilted through an arc of approximately 15°, the table comes into contact with a stop 144 which is mounted on a channel 18 in the path of an arm 146 secured to the sleeve 84. When the loaded table comes to a stop to separate the loaded table from the end of the lanes, a carton may be placed over the containers on the end. Thereafter, a switch 148, Fig. 9, may be operated to actuate a solenoid 150 to withdraw the stop to permit the table to complete its tilting operation to the position illustrated in Fig. 5. The switch 148 is a spring pressed switch so that when pressure is released from the switch, the solenoid will be de-energized to permit a spring 152 to draw the stop 144 back into the path of the arm 146.

The stop 144 is shown more particularly in Figs. 11 and 12 and has a rectangular cross section which moves through a square opening 154 in the channel 18, Fig. 9. When the stop is withdrawn from the path of the arm 146, the continued movement of the table by means of the piston rod 122 will move the arm 146 past the stop and immediately the spring 152 will project the stop 144 into the path of the arm. An inclined face 154 is formed on the stop 144 in the path of movement of the arm so that when the table is moving into loading position the arm strikes the inclined face 154 to force the stop back into the solenoid to allow the table to pass the stop. When the table is tilted, however, the arm strikes the top face of the stop to stop the movement of the table and the table will be held against the pulling pressure of the piston rod 122 until the solenoid 150 withdraws the stop from the path of the arm 146. The arm 146 has an inclined face 156 which engages the face 154 to reduce the friction in forcing the stop out of the path of the arm. The rear end of the arm 146 is curved at 158 to fit over the sleeve 84, the arm being secured in rigid position by welding the arm to the sleeve.

The two-step movement for tilting the table is only necessary for the convenience of the operator and for speeding up the operation of packaging short neck bottles. If the containers have a shape which will permit the carton to be readily placed thereon then the two-step movement of the table is not required.

The electric power for operating the motors and solenoids is connected with switch box 160 and fuse box 162. The fuse box 162 is connected with a starter 164 for motor 34, and a starter 166 is for motor 66. The switch 130 is connected with the fuse box 162 and solenoid 110. The switch 134 is connected with the fuse box 162 and solenoid 112. The switch 148 is connected with the fuse box 162, and with the solenoid 150. When the solenoid 110 is put into operation, it holds the four-way valve in position to operate the table tilting plunger 98. When the solenoid 112 is put into operation, it opens the air supply valve 108 to operate the plunger 98 to return the table to loading position and maintains the air supply to exert pressure for holding the table in loading position until the switch 130 is again operated to energize solenoid 110.

The packaging machine herein described and claimed is well adapted for packing containers in cartons, whether metal, glass or other material, in a single layer. The machine is particularly adapted for arranging containers so that they may be put readily in cells of a carton.

The preferred form of the invention having been thus described, what is claimed as new is:

1. A container packaging machine comprising a support, a conveyor belt mounted for movement in a closed cycle at the top of the support, means to move the conveyor, side guides at the front end of the conveyor belt for the heterogeneous assembly of containers, a series of distributing plates supported above the belt, said plates being sufficiently wide to arrange comparatively tall containers in upright position and being movably suspended in vertical position from one edge with the other edge closely adjacent the belt and spaced apart a distance slightly greater than the width of the container being packaged, means to oscillate the front ends of the plates transversely of the belt to guide containers from the assembly station into the lanes arranged between the plates, a tilttable table mounted at the rear end of the belt with its upper surface in alignment with the top of the belt to receive containers from the belt, positioning means on the table arranged to assemble a definite number of containers from the belt in position for the insertion of a carton thereover, means for tilting the table to discharge a loaded carton therefrom upside down, a yieldably mounted conveyor positioned to receive the discharged carton, a stop mounted at the front edge of the table, and means to move the stop in front of the rows of containers on the belt to hold back the containers while the conveyor continues to operate as the table is tilted.

2. The packaging machine defined in claim 1 in which the front end of the distributing plates are provided with a notch arranged to prevent engagement of the plates with the containers in the area of the labels on the containers.

3. The packaging machine defined in claim 1 in which the front end of the distributing plates are provided with a bead to engage the bottoms of containers to align them in rows between the plates.

4. The packaging machine defined in claim 1 in which the tilting table has a convex upper surface to spread the upper portions of the containers apart to arrange the containers to receive a carton having a cell for each container.

5. The packaging machine defined in claim 1 in which the tilting table is tilted by a double-acting, air-operated piston against which the air acts while the table is in loading position to positively hold the table in loading position.

6. The packaging machine defined in claim 5 in which air pressure lines are connected with each end of the double acting piston, and a manual control valve in the air line is operated to tilt the table for discharging a packed carton of containers.

7. The packaging machine defined in claim 6 in which the tilting movement of the table is composed of two steps, the first step consisting of a short table movement to bring an arm on the table against a stop to separate the containers on the table from the containers in the lanes over the belt to permit the carton to be placed over the containers, and the second step caused by the manual operation of a switch to withdraw

the stop to permit the table to complete its tilting movement.

18. The packaging machine defined in claim 7 in which the air pressure remains on the plunger piston for tilting the table while the table is against the stop in the first step of movement, and means are provided to withdraw the stop from the table holding position to permit the plunger piston to complete the second step of the table tilting movement.

9. The packaging machine defined in claim 6 in which a solenoid operating electric switch is mounted on the support in the path of movement of the table to operate an air control valve to reverse the operation of the plunger piston to return the table from carton discharging tilted position to loading position.

10. The packaging machine defined in claim 9 in which the switch is adjustable in position to limit the amplitude of tilting movement to provide for reversing the table loaded with cartons of different sizes.

11. The packaging machine defined in claim 1 in which the positioning means on the table consists of side guides which form a continuation of the guide plates, and a back stop adjustably mounted on the table in the line of movement of the containers.

12. The packaging machine defined in claim 1 in which the stop for the containers on the belt is moved into the path of lanes of containers by an air-operated plunger piston and a manually controlled valve in the line for supplying air to the piston is actuated to supply air to the plunger piston simultaneously with the initiation of the operation of the table tilting mechanism.

13. The packaging machine defined in claim 12 in which air is applied to the container stop operating plunger to move the stop into container-stopping position during the entire tilting and return strokes of the table and an air-escape valve in the cylinder to permit air to escape from the cylinder of the stop-operating plunger to permit the table to positively engage and move the stop down when the table is returned to loading position.

14. The packaging machine defined in claim 13 in which the container stop is positioned under the front edge of the table by the plunger and moves up with the table when the table is tilted to discharge a loaded carton.

15. The packaging machine defined in claim 1 in which the conveyor belt is a woven wire belt with a herringbone weave which will slide under the containers without producing a movement of the containers transversely of the belt when the containers on the belt are held from movement by the stop.

16. In a packaging machine, a mechanism for assembling containers for packaging, and the upper end of the loaded package comprises a conveyor belt mounted for cyclic movement at the top of the table, means mounted over the belt to arrange the containers to be packaged in rows of a single container width on the belt, a table having its front edge at the same level as the top of the belt, a series of guides on top of the table positioned to receive containers from the rows on the belt, a table container stop at the rear side of the table, said guides and stop being mounted to arrange containers to permit a carton having an individual cell for each container to be moved down over the containers and means to tilt the table about an axis transverse to the

line of movement of the belt to discharge a loaded carton with its bottom side up.

17. The table operating mechanism defined in claim 16 in which the upper face of the table is convex.

18. The table operating mechanism defined in claim 16 in which a belt container stop is mounted under the front edge of the table in position to be moved down by the table below the table level when the table is moved into loading position.

19. Table operating mechanism defined in claim 18 in which the belt container stop is moved up into stopping position by an air-operated plunger piston having an air pressure connection at the bottom of the plunger to force the piston upwardly and a valve connected to the cylinder having a regulated opening to slowly bleed air therefrom to positively hold the stop in stopping position while the table is tilted.

20. A table operating mechanism defined in claim 16 in which the table is tilted by a double-acting piston, air supply lines connected to each end of the piston cylinder, a multi-passage electric solenoid operated valve in the air supply lines, an electric switch to operate the solenoid valve to supply air to one end of the cylinder to move the table to carton-discharging position, and a switch mounted in the path of movement of the table to stop the table tilting movement and to operate a solenoid to operate the valve to supply air to the other end of the cylinder to positively return the table to loading position.

21. The operating mechanism defined in claim 20 in which a piston connected with the belt container stop is connected with the air supply line which supplies air to the table tilting piston whereby air is simultaneously supplied to the belt container stop piston when air is supplied to the table tilting piston.

22. The table operating mechanism defined in claim 20 in which a table tilting stop is normally held by a spring in position to stop the table after moving through an arc of approximately 15°, a solenoid is used for moving the stop, a manually controlled electric switch is connected with the solenoid to withdraw the table stop from the movement of the table as long as the solenoid is energized, and a cam is mounted on the table in position to move the stop out of table-stopping position during the return movement of the table from the tilted position to container-loading position.

23. The table operating mechanism defined in claim 20 in which the solenoid valve when operated to return the table to loading position maintains air pressure on the table tilting plunger to hold the table in loading position until the valve is operated to supply air for tilting the table.

24. The table operating mechanism defined in claim 20 in which an electrically operated solenoid stop is mounted below the table to engage and stop the table when it has tilted through a small arc to separate containers on the table away from the rows of containers on the belt and a manual electrically operated switch is connected with the table solenoid stop to release the table from the stop after a carton has been placed over the containers on the table.

25. The table operating mechanism defined in claim 24 in which the solenoids for controlling the two table tilting steps are actuated by manual controlled electric switches.

11

26. A machine for placing containers in the cartons comprising a conveyor having a receiving end and a discharge end for transporting the containers in upright position and having means extending therealong and for arranging the containers thereon in rows, a stop at the discharge end of the conveyor movable into and out of a container obstructing position for controllably restraining the containers against movement while the conveyor continues to operate, an assembly table at the discharge end of the conveyor for receiving a group of containers from the conveyor, said table having a convex surface whereby the axes of the upright containers are

10

12

caused to diverge upwardly when the containers are grouped on said table, whereby a carton having individual container partitions may be readily placed over the group of containers, and a means for operating the stop.

RICHARD A. SMITH.
